UNITED STATES PATENT OFFICE.

LEONARD A. LAMAR AND PETER BORGAN, OF PORTLAND, OREGON.

LIFE-SAVING APPARATUS.

1,273,383.

Specification of Letters Patent. Patented July 23, 1918.

Application filed July 19, 1917. Serial No. 181,483.

To all whom it may concern:

Be it known that we, LEONARD A. LAMAR and PETER BORGAN, citizens of the United States of America, residing at Portland, in the county of Meigs and State of Oregon, have invented certain new and useful Improvements in Life-Saving Apparatus, of which the following is a specification, reference being had therein to the accompanying drawing.

This invention relates to a life saving suit, and has for its object the production of a simple and efficient suit, within which a person may float upon the surface of the water without danger of being drowned.

Another object of this invention is the production of an efficient life saving suit, which is adapted to entirely envelop a person, and permit him to float upon his back.

With these and other objects in view this invention consists of certain novel combinations and arrangements of parts as will be hereinafter fully described and claimed.

In the drawings:

Figure 1 is a front elevation of the life saving suit.

Fig. 2 is a rear elevation of the life saving suit.

Fig. 3 is a front elevation of the inner hood.

Fig. 4 is a section taken on line 4—4 of Fig. 3.

Fig. 5 is a section taken on line 5—5 of Fig. 1.

Fig. 6 is a detail perspective of the back floating compartment.

Fig. 7 is an end view of the back floating compartment, showing the manner of connecting the same to the inner face of the suit.

Fig. 8 is a perspective view of the block, which is adapted to constitute the string holder.

By referring to the accompanying drawings, it will be seen that 1 designates the body of the suit, which is provided with suitable arm portions 2, and leg portions 3, which portions are adapted to conform to the contour of the wearer. The body 1 of the suit is provided with an open neck, which is of suitable size to permit a person to get within the suit 1. The upper neck portion of the suit or body 1, is provided with a folded portion 4 within which is mounted a drawing string 5, this string being anchored at a suitable or convenient point for

permitting the neck of the suit 1 to be drawn tightly around the neck of the wearer, or the hoods carried by the suit, as will be hereinafter described.

The string holder block 6 is carried by the front of the suit 1, and is provided with a plurality of apertures 7 formed therein, through which apertures 7 pass the respective ends of the drawing string 5; the block 6 holds the ends of the string 5 close together and readily accessible to the wearer of the suit. Suitable loops 8 are formed upon the ends of the drawing string 5, to permit the same to be conveniently and easily handled, and also to permit the neck portion of the suit 1 to be drawn tightly around the outer hood.

A back float 9 is secured to the rear of the suit 1, and this back float 9 is provided with a plurality of laterally extending lugs 10 at the corners thereof, for permitting the same to be engaged by means of the spring clasps 11, carried by the suit 1, thereby permitting the back float 9 to be conveniently attached to or detached from the suit 1. This back float 9 is provided with a concave inner face, in order to permit the same to snugly fit around the back of the wearer. A suitable float 12 of the same construction as that described and illustrated clearly in Fig. 6, is secured to the front of the suit upon the inner face thereof, to add buoyancy to the suit.

A flexible inner hood 13 is adapted to fit over the head of the wearer, and this inner hood 13 is provided with a suitable peephole transparent sheet 14 attached to the front thereof, having suitable air inlet apertures 15 formed therein. This hood 13 is adapted to fit over the head of the wearer and forms an additional protection for the wearer; this hood 13 contains a float tank 16, which tank 16 is adapted to constitute a pillow for the head of the wearer, should he be floating upon his back.

An outer flexible hood 17 is adapted to fit over the inner hood 13 as shown in Fig. 4, and this outer hood 17 is provided with a plurality of transparent side openings 18 formed in the front thereof, which are adapted to register with the peep hole 14 in the hood 13. A plurality of air inlet apertures 19 are formed in the front of the hood 17 and register with the apertures 15 of the inner hood 13, and these apertures 19 are normally closed by means of doors or corks

20, which corks are anchored upon the hood 17 by means of the chains or strings 21. From the foregoing description, it will be seen that a very simple and efficient suit has 5 been produced, within which a person may place himself, and in this way be secure from drowning. The suit may be readily placed upon the wearer, and drawn tightly around the hoods, in order to prevent water 10 from entering the same. The tanks 9, 12 and 16 will afford sufficient buoyancy to support the wearer of the garment. It should be understood that the string holder block 6, is secured to the suit.

15 What is claimed is:—

1. A life saving suit, of the class described, comprising a body, buoyancy tanks secured to said body upon the back and front thereof, a removable hood coöperating with 20 said body, a drawing string secured to the neck portion of said body, and a string hold-

ing block secured to said suit, said drawing string passing through said block, and adapted to be firmly held therein, in a set position, and loops carried by the ends of 25 said string for permitting said string to be drawn tightly around said hood.

2. A life saving suit, of the class described, comprising a body, buoyancy means carried thereby, an inner protective hood, an outer protective hood, means for drawing said suit tightly around said outer hood, said inner hood provided with apertures formed therein, said outer hood also provided with air inlet apertures registering with the apertures of the inner hood, and releasable corks anchored upon said body and adapted to close said apertures of the outer hood. 30 35

In testimony whereof we hereunto affix our signatures.

LEONARD A. LAMAR.
PETER BORGAN.
